DESIGN FOR A DRAWER PULL

Allan F. Jones, Jamestown, N. Y., assignor to
Sack Incorporated, Boston, Mass., a corpora-
tion of Massachusetts

Application December 12, 1935, Serial No. 60,031

Term of patent 3½ years

To all whom it may concern:

Be it known that I, Allan F. Jones, a citizen of the United States and a resident of Jamestown, county of Chautauqua, and State of New York, have invented a new, original, and ornamental Design for a Drawer Pull, of which the following is a specification, reference being made to the accompanying drawing, forming part thereof.

In the drawing showing my new design:

Fig. 1 is a plan view;

Fig. 2 is a front elevation;
Fig. 3 is a side elevation, and
Fig. 4 is a cross-section on the line 4—4 of
Fig. 2.

The dominant feature of my design resides in the grooved portions of the drawer pull.

I claim:

The ornamental design for a drawer pull, as shown and described.

ALLAN F. JONES.
